UNITED STATES PATENT OFFICE

2,477,724

PROTRACTOR

Alfred R. Creain, Covington, Ky.

Application July 19, 1947, Serial No. 762,157

8 Claims. (Cl. 33—91)

1

The present invention relates to a protractor for use in connection with a straight edge by draftsman and the like.

An object of the invention is to provide a protractor device affording accurate layout of angles from a straight edge.

Another object of the invention is to provide a device of this character that is capable of rapid adjustment to simultaneously attain selected equal angles on either side of a vertical center line.

Still another object of the invention is to provide a protractor enabling the layout of lines that are at right angles to each other and on opposite sides of a vertical center line.

A further object of the invention is to provide for the simultaneous layout of selected equal angles from the vertical and the horizontal so that the complements of said angles are likewise available.

A still further object of the invention is to provide a device affording a layout of lines closer to a straight edge than that afforded by other available instruments of similar nature.

It is a special object of the invention to provide an instrument which is easily set to attain accurate angle measurements together with the opposite and the complement thereof without necessity of mathematical calculation and a new adjustment based on such mathematical calculation.

These and other objects are attained by the means described herein and disclosed in the accompanying drawings, in which:

Fig. 1 is a fragmental top plan view of a protractor of the invention.

Fig. 2 is a bottom end elevational view of the device of Fig. 1.

Fig. 3 is a cross-sectional view taken on line 3—3 of Fig. 2, and showing in full and dotted lines the limits of adjustment of the straight edges.

Fig. 4 is a cross-sectional view taken on line 4—4 of Fig. 1.

Fig. 5 is a cross-sectional view taken on line 5—5 of Fig. 1.

Fig. 6 is a cross-sectional view taken on line 6—6 of Fig. 1.

Fig. 7 is a cross-sectional view taken on line 7—7 of Fig. 1.

Fig. 8 is a cross-sectional view taken on line 8—8 of Fig. 1.

The protractor of the invention comprises a relatively flat hollow housing 10 having a straight edge 11 adapted to rest against the straight edge

2

(not shown) which is used with the drawing board. Within the hollow housing 10 are contained co-operating elements (hereafter described) whereby associated straight edges 12, 13, 14, and 15 are simultaneously moved toward uniform angles of adjustment about two pivot studs 16 and 17 which are suitably journaled in the upper and lower parts of the housing 10.

Referring now to Figs. 1, 3 and 8 it will be seen that stud 16 has an intermediate shoulder or angular flange 18 below which is a gear segment 19 journaled on the stud between the bottom of housing 10 and flange 18. Segment 19 has an integral arm 20 to which straight edge 13 is secured in suitable fashion as by screws 21. It will be noted further that another gear segment 22 is mounted for rotation on the stud 16 between the top of flange 18 and the upper half of housing 10. Segment 22 has an integral arm 23, to the bottom of which the straight edge 12 is secured by means of screws such as 21. The gear segments 19 and 22 are recessed on adjacent faces and coiled spring 24 is disposed in the space between the segments and surrounding flange 18. As can be best seen in Figs. 3 and 4 spring 24 has its respective opposite ends turned upwardly and downwardly from the plane of the coil and anchored to the segments 19 and 22 respectively by entering the ends 26 and 27 into perforations in said segments. In a generally similar arrangement stud 17 has an integral shoulder 28 and serves as a pivotal support for an upper gear segment 29 and a lower gear segment 30 the respective segments having arms 31 and 32 to which the straight edges 14 and 15 respectively are secured. A pinion 33 is journaled on a stud 34 and meshes with the upper gear segments 29 and 22 so that arms 23 and 31 carrying straight edges 12 and 14 are moved simultaneously and in the same direction whenever movement is imparted to either of them. It will be noted that the straight edges 12 and 14 are at right angles to each other.

In a similar fashion the lower gear segments 19 and 30 are arranged to mesh with a pinion 35 which is journaled on a stud 36 having an upwardly projecting integral screw stud 37. These lower gear segments 19 and 30 carry arms 20 and 32 respectively to which straight edges 13 and 15 are attached. Thus the movement of arm 13 or 15 will impart to the remaining arm a like motion and in the same direction. It should be now observed that pinion 35 also meshes with pinion 33, which latter pinion meshes with the segment carrying the arms to which straight edges 12 and 14 are attached. Hence the move-

ment of straight edge 15, for example, from the full line position in Fig. 3 to the dotted line position thereof will impart a precisely corresponding movement of straight edge 13 from its full line position to its dotted line position. This much of the movement is afforded through segment 30, pinion 35, and segment 19. This movement of pinion 35 will afford a corresponding movement of pinion 33 in the opposite direction so that straight edges 12 and 14 will be simultaneously moved from the full line position to the dotted line position.

The initial disposition of arms 20 and 32 at right angles to each other and arms 23 and 31 at right angles to each other is maintained by the action of the springs 24 in their respective sets of superposed segments. The springs are at all times in opposition to any play in the teeth of the pinions and segments.

A generally quadrant shaped sheet metal plate 38 has a flatwise sliding movement on the top of housing 10 and it is fixed with the stud 34 so as to move therewith as the arms carrying the straight edges are moved. The mounting may be effected by means of a washer 39 which is slightly sunken in a suitable annular recess in the top of plate 38, said washer and plate being secured to the top of stud 34 by means of a screw 40 which is threadedly entered into a tapped hole in said stud. A pin 41 is passed eccentrically through the washer and plate and into said stud before the screw 40 is attached.

Plate 38 has an arcuate slot 42 formed on a radius having stud 34 as a center and located so as to enable the screw stud 37 on the top of stud 36 to extend through the slot and permit movement of the plate 38. A threaded cap or nut 43 on screw 37 may be tightened to bind the plate 38 against movement over the top of the housing 10 and it thus serves to hold the straight edge scales 12, 13, 14 and 15 in adjusted positions when desired.

The edge of plate 38 is grooved and it rides on a concentric tongue or rib 44 of an index plate 45.

The matching edges of the relatively moveable plates 38 and 45 are provided with graduated scales for the purpose of enabling rapid and accurate adjustments of the straight edges to selected angles. A 90° arc on the edge of plate 38 is divided to provide indexing marks representative of forty-five degrees of adjustment and at both ends a few additional like graduations are provided. The graduations are marked with a double set of figures which indicate respectively 0° to 45° and 45° to 90°. The fixed plate 45 has a zero index line at its center and is graduated on opposite sides thereof with subdivisions representing minutes for plus or minus reading and adjustment. The effect of the moveable angle scale and the fixed minutes scale is substantially that of a vernier adjustment.

It will be understood that the specific structural details of the device as illustrated may be subject to modification within the spirit of the invention and the scope of the appended claims.

The operation of the device will be readily apparent to those conversant with the graphic mechanical arts. It will be noted that the springs 24 operate to resist play in the meshing engagement of the several segments and pinions and hence accurate adjustments of the straight edges to selected angles may be relied upon. In use the straight bottom edge 11 of the housing would be placed against the straight edge on the draw-

ing board. The ends of the straight edges 12, 13, 14 and 15 adjacent housing 10 will be noted to be at all times closer to the straight edge on the drawing board than is possible with the selectively adjustable devices of this general character now available. When an adjustment to a given angle is to be made with one side of one of the straight edges, the cap or nut 43 is loosened and the selected adjustable straight edge e. g. 15 is merely moved to the desired angle. In moving one straight edge 15 a given number of degrees away from the horizontal, the corresponding straight edge 12 moves a like number of degrees from the horizontal on the opposite side of the vertical center line. At the same time straight edges 13 and 14 move away from the vertical center line in opposite directions so that they assume angles which are the complement to that to which the associated straight edge was set. Furthermore straight edges 12 and 14 will also remain at right angles to each other throughout the full range of adjustment and straight edges 13 and 15 which are right angles also will remain at right angles to each other. The vernier adjustment enables the user to avoid error of adjustment according to an incorrect mathematical calculation as well as the mechanical error of adjustment to a mathematical calculation which sometimes occurs, particularly where it is desired to lay out an angle in degrees and minutes at one place and to also lay out the complement of said angle, possibly as an opposite complement. For example, if the straight edge 13 is to be set at 70° 20' it would be moved until the character 70 on the plate 38 registers with the 0 on plate 45 then it would be shifted further until the 20' mark matches with the next succeeding mark on plate 38. The cap 43 may then be tightened to bind the parts against movement, whereupon it would be found that the straight edge 14 has been moved to an opposite angle of 70° 20' and the straight edges 12 and 15 will have assumed opposite angles of 19° 40', which are the complement to the settings of the associated straight edges. The layout of beveled gear trains in machine drawings will be appreciated as a simple example of the effectiveness of the protractor of the present invention both as to accuracy and as to time saving.

What is claimed is:

1. In a protractor the combination of a flat hollow housing, a pair of pivot studs in the housing in spaced parallel relation, a pair of superposed gear segments on each stud, a pair of straight edge members disposed at right angles to each other and mounted respectively for movement with the lower gear segments, a pinion intermediate and meshing with said lower gear segments, a second pair of straight edge members disposed at right angles to each other and mounted respectively for movement with the upper gear segments, and a second pinion intermediate and meshing with the upper gear segments and also meshing with the first mentioned pinion.
2. In a protractor the combination of a flat hollow housing, a pair of pivot studs in the housing in spaced parallel relation, a pair of superposed gear segments on each stud, a pair of straight edge members disposed at right angles to each other and mounted respectively for movement with the lower gear segments, a pinion intermediate and meshing with said lower gear segments, a second pair of straight edge members disposed at right angles to each other and

mounted respectively for movement with the upper gear segments, and a second pinion intermediate and meshing with the upper gear segments and also meshing with the first mentioned pinion, one straight edge of each of said pairs of straight edges being disposed at all times intermediate the straight edges of the other pair.

3. In a protractor the combination of a flat hollow housing, a pair of pivot studs in the housing in spaced parallel relation, a pair of superposed gear segments on each stud, a pair of straight edge members disposed at right angles to each other and mounted respectively for movement with the lower gear segments, a pinion intermediate and meshing with said lower gear segments, a second pair of straight edge members disposed at right angles to each other and mounted respectively for movement with the upper gear segments, a second pinion intermediate and meshing with the upper gear segments and also meshing with the first mentioned pinion, and externally disposed means for securing one of said pinions against movement for retaining all of the segments and the associated straight edges in adjusted positions.

4. In a protractor the combination of a flat hollow housing, a pair of pivot studs in the housing in spaced parallel relation, a pair of superposed gear segments on each stud, a pair of straight edge members disposed at right angles to each other and mounted respectively for movement with the lower gear segments, a pinion intermediate and meshing with said lower gear segments, a second pair of straight edge members disposed at right angles to each other and mounted respectively for movement with the upper gear segments, a second pinion intermediate and meshing with the upper gear segments and also meshing with the first mentioned pinion, a quadrant shaped plate fixed for movement with one of said pinions and slidable over the exterior of the housing, said plate having graduations denoting degrees of angular adjustment of the segments and associated straight edges; and a fixed plate on the housing having at least one indexing line.

5. In a protractor the combination with a pair of spaced apart parallel studs, of a lower gear segment on each stud, an upper gear segment on each stud, a pair of pinions meshing with each other, one of said pinions meshing with the lower segments, the other of said pinions meshing with the upper segments, straight edges fixed to the respective lower segments and disposed at right angles to each other, straight edges fixed to the respective upper segments and disposed at right angles to each other, and spring members yieldably urging the companion upper and lower segments in opposite directions.

6. A protractor comprising a pair of parallel studs, straight edge members having toothed segmental ends mounted for movement about said studs as centers, said members disposed at right angles to each other, a pinion meshing at oppo-

site sides with the respective toothed segmental ends, and means yieldably urging the segments into toothed driving engagement with the pinion in one common direction, and yieldably resisting toothed driving engagement thereof with the pinion in the opposite direction.

7. A protractor comprising a housing having a straight bottom edge and provided with slots extending longitudinally through the remaining edges, two spaced apart pairs of superposed concentric gear segments rotatably mounted within said housing and each having a tangential arm extending through an edge slot in the casing, and a pair of mutually meshing pinions rotatably mounted intermediate said spaced pairs of gear segments and meshing respectively with the upper gear segments and the lower gear segments respectively of said spaced pairs of gear segments, the arms of the lower gear segments being disposed at ninety degrees to each other and the arms of the upper gear segments being disposed at ninety degrees to each other, the said pinions retaining said ninety degree angularity of said arms during rotary movement of the meshing pinions and segments, and serving to simultaneously move the arms of the lower gear segments in one direction and the arms of the upper gear segments in the opposite direction.

8. A protractor comprising a housing having a straight bottom edge and provided with slots extending longitudinally through the remaining edges, two spaced apart pairs of superposed concentric gear segments rotatably mounted within said housing and each having a tangential arm extending through an edge slot in the casing, a pair of mutually meshing pinions rotatably mounted intermediate said spaced pairs of gear segments and meshing respectively with the upper gear segments and the lower gear segments respectively of said spaced pairs of gear segments, the arms of the lower gear segments being disposed at ninety degrees to each other and the arms of the upper gear segments being disposed at ninety degrees to each other, the said pinions retaining said ninety degree angularity of said arms during rotary movement of the meshing pinions and segments, and serving to simultaneously move the arms of the lower gear segments in one direction and the arms of the upper gear segments in the opposite direction, and spring means urging each pair of superposed gear segments in opposite directions and into toothed driving engagement with the pinion meshing therewith.
